UNITED STATES PATENT OFFICE

2,145,837

CARRIAGE RAIL SUPPORT FOR KNITTING MACHINES

Ladislaus Robaczynski, Brooklyn, N. Y.

Application April 30, 1936, Serial No. 77,082

11 Claims. (Cl. 66—63)

This invention relates to new and useful improvements in knitting machines of the so-called "links and links" type, and more particularly, it pertains to a new and improved carriage rail support for such machines.

Machines of the so-called "links and links" type consist of a frame in which is mounted a pair of needle beds over which travels a carriage. The carriage is supported by and movable over two rails which extend substantially through the length of the machine, and one of which is known as the front rail, the other being known as the back rail. These rails form a track over which the carriage travels, and due to the construction of the machine, the rear carriage rail has been heretofore attached to the machine only at its ends, there being no intermediate attachment for the rail. Such a construction has been found to have disadvantages in that, in the case of relatively long machines, this rear carriage rail has a tendency to get out of true alinement, thereby throwing the carriage out of proper relation to other parts of the machine with which, in order to produce the best results, it is necessary to maintain alinement.

It is the object of the present invention to improve the construction of the rear carriage rail of "links and links" knitting machines and to provide means whereby adjustment of the rear carriage rail is provided.

A feature of the invention resides in a new and novel construction and arrangement of parts whereby the rear carriage rail of a "links and links" knitting machine may be supported at a number of points throughout its length.

A further feature of the invention resides in the provision of a new and novel form of supporting means which will permit of adjustment of the rear needle rail in such a manner that any sagging which might be present may be removed.

A further feature of the invention resides in the provision of new and novel means whereby the rear carriage rail of a knitting machine may be adjusted in a lateral direction.

It is still a further feature of the invention so to construct the lateral adjusting means that the carriage rail will be held against accidental displacement in the position to which it may be adjusted by said means.

A still further feature of the invention resides in the provision of means whereby the supporting means may be retained in its adjusted position.

Various other features of the invention will become apparent as the nature thereof is better understood, and reference will, therefore, be had

to the following specification and claims and the accompanying drawings, in which:

Figure 1 is a view in elevation partly broken away showing a rear view of a portion of a "links and links" knitting machine,

Figure 2 is a transverse sectional view taken substantially on the line 2—2 of Figure 1,

Figure 3 is a similar view taken substantially on the line 3—3 of Figure 1,

Figure 4 is a distended perspective view illustrating the new support,

Figure 5 is a fragmentary view in rear elevation partly broken away of a portion of a knitting machine frame illustrating a modified form of the invention,

Figure 6 is a transverse sectional view on an enlarged scale taken substantially on the line 6—6 of Figure 5,

Figure 7 is a transverse vertical sectional view taken substantially on the line 7—7 of Figure 5, 20 the view being enlarged,

Figure 8 is a horizontal sectional view on an enlarged scale and taken substantially on the line 8—8 of Figure 5, and;

Figure 9 is a detail distended perspective view. 25

Referring to the drawings, and particularly to Figures 1 and 4, inclusive, the reference numeral 5 designates the frame of a "links and links" knitting machine, which frame may be of any approved desired construction. The reference 30 numeral 6 designates the rear needle bed which is provided with grooves 7 in which are mounted for free sliding movement needle jacks 8 and needle jack pushers 9.

It is because of the presence of the rear ends 35 of the needle jack pushers 9 beneath the rear carriage rail which is designated 10, that means for supporting the rear carriage rail 10 at points intermediate of its ends has heretofore been a problem, and it is the overcoming of this prob- 40 lem that the present invention aims to effect.

In the general construction of machines of this type, a comb rail 12 having a plurality of spaced teeth receives the rear end of the jack pushers 9 to support the same when they are in their fully extended position, as illustrated in Figure 2. This comb rail is generally supported by a bracket 13 secured to the frame in any desired manner, such as by bolts 14, as illustrated in Figure 1. The devices of the present invention are adapted to be secured to this comb rail 12 and are adapted to engage beneath the carriage rail 10. These devices consist of a block 15 which, as more clearly illustrated in Figure 4, 45 consists of a main body portion having a lug 50

16, a plurality of elongated slots 17 and a plurality of spaced teeth, the latter being formed upon the upper edge of the block. The teeth 18 are of substantially the same dimensions as the teeth of the comb rail 12 and the spaces between the teeth 18 of the block 15 will also be of the same dimensions as the space between the teeth of the comb rail. The blocks 15 are adapted to be secured to the comb rail 12 by means of bolts or the like 19 which pass through the slots 17 and engage threaded openings in the comb rail 12. When the blocks 15 are placed upon the comb rail it will be understood that the teeth 18 of the blocks will be lined up with the teeth of the comb rail in order that the rear ends of the several jack pushers 9 may pass as freely through the blocks 15 as they do through the comb rail 12.

Means is provided to adjust the blocks 15 relative to the carriage rail 10, and this means consists of a threaded bolt 25 threaded in an opening 26 in a bracket arm 27, which in turn is secured to the frame 5 by means of bolts 28, see Figure 3. The upper end of the bolt 25 engages the under face of the lug 16 of the block 15, as illustrated in Figure 3.

From the foregoing construction it will be apparent that if the bolts 19 are loosened, the block 15 may be moved vertically either upwardly or downwardly merely by an adjustment of the bolt 25. After the bolt 25 has been properly adjusted, a jam nut 30 may be adjusted to hold the bolt 25 in its adjusted position. After the block has been adjusted to the desired position, the bolts 19 are tightened, clamping the block 15 to the comb rail 12 in order that the block may be held in its adjusted position.

While in the foregoing specification, the device has been described as a single device, it is to be understood that any number of these devices may be employed and that in the case of a number of such devices being employed, they will be independently operable as to adjustment, thus providing means whereby the rear carriage rail of a "links and links" knitting machine may be supported at points intermediate of its ends, and further, that the supports are adjustable in order that the rear carriage rail may be adjusted to remove therefrom any sagging which may be present therein and to support the carriage rail in a manner which will prevent sagging thereof.

In the modified form of the invention illustrated in Figures 5 to 9, inclusive, the frame 5, bracket arm 27, threaded bolt 25, jam nut 30, and comb rail 12 are of substantially the same construction as in the preferred form of the invention heretofore described.

The blocks, in this form of the invention, however, are different from the blocks 15 heretofore described in that said blocks, which are designated 60, are provided with three elongated openings 61, 62, and 63. The elongated slot 62 is disposed centrally of the block 60, the slots 61 and 63 being located closely adjacent the ends thereof. In this form of the invention the blocks are also provided with two threaded openings 64, and these threaded openings 64 are located between the central elongated slot of the end slots, as shown in Figure 9. In this form of the invention, the blocks 60 are secured to the comb rail 12 by bolts 66 and 67 which pass through the elongated slots 61 and 63 respectively in the block 60, and have threaded engagement with the comb rail 12. The blocks 60 are also sup-

ported from the angle bracket 68 by means of a bolt 69 which has threaded engagement with the angle bracket as at 70 in Figure 8.

The construction just described provides for vertical adjustment of the blocks 60 in order that any sag in the carriage rail 80 may be eliminated merely by elevating one or more of the blocks 60 until the carriage rail is in its proper position after which the remaining blocks are moved into supporting engagement with the 10 under surface thereof.

In this form of the invention means is provided for lateral adjustment of the carriage rail, and this means consists of two bolts 72 which are threaded into openings 64 in the blocks 60 and have engagement with the comb rail 12, as illustrated in Figure 8. It will be noted that in this form of the invention the toothed edge of each block 60 is received in a recess 76 in the carriage rail 80. This construction is provided so that when the blocks 60 are moved laterally, the rail 80 will be moved in the same direction by reason of interengagement with the teeth of the blocks 60 in the recesses 76 in the rail.

To effect an adjustment in a lateral direction, for instance to the right in Figures 6 and 7, the bolts 66, 67 and 69 will be backed out while the bolts 72 will be tightened into engagement with the comb rail 12, thus moving the block to the right in said Figures 6 and 7. To effect an adjustment to the left in said Figures 6 and 7, the bolts 72 will be backed out while the bolts 66 and 67 will be tightened to move the block 60 to the left in Figures 6 and 7.

From the foregoing it will be seen that the modified form of the invention provides, in addition to means for adjusting the carriage rail in a vertical direction, means by which the carriage rail may also be adjusted laterally, thus providing means for full adjustment of the carriage rail.

While the invention has been herein disclosed in its preferred forms, it is to be understood that it is not limited to the specific construction herein illustrated and that it may be practiced in other forms without departing from the spirit thereof.

Having thus described the invention, what is claimed as new, is:

1. In a links and links knitting machine, in combination, a comb rail, a carriage rail, means carried by the comb rail and movable into engagement with the carriage rail for supporting the carriage rail from the comb rail, and means for adjustably securing said supporting means from said comb rail.

2. In a links and links knitting machine, in combination, a frame, a comb rail supported upon said frame, a carriage rail, and means for supporting said carriage rail from said comb rail, said carriage rail supporting means comprising a plurality of blocks arranged in spaced relation upon said comb rail, and means for adjusting said blocks relatively to the comb rail and the carriage rail.

3. In a links and links knitting machine, in combination, a frame, a comb rail supported upon said frame, a carriage rail, and means for supporting said carriage rail from said comb rail, said carriage rail supporting means comprising a plurality of blocks arranged in spaced relation upon said comb rail, means for adjusting said blocks relatively to the comb rail and the carriage rail, and means for securing said blocks in their adjusted positions.

4. In a links and links knitting machine, in combination, a frame, a comb rail supported upon said frame, a carriage rail, and means for supporting said carriage rail intermediate of its ends from said comb rail, said carriage rail supporting means including a plurality of blocks arranged in spaced relation upon said comb rail, and means for individually adjusting said blocks relatively to the comb rail and the carriage rail.
5. In a links and links knitting machine, in combination, a frame, a comb rail supported upon said frame, a carriage rail, and means for supporting said carriage rail intermediate of its ends from said comb rail, said carriage rail supporting means including a plurality of blocks arranged in spaced relation upon said comb rail, and means for individually adjusting said blocks relatively to the comb rail and the carriage rail, said last mentioned means being carried by said frame.
- 10 6. In a links and links knitting machine, in combination, a frame, a comb rail supported upon said frame, a carriage rail, and means for supporting said carriage rail intermediate of its ends from said comb rail, said carriage rail supporting means including a plurality of blocks arranged in spaced relation upon said comb rail, means carried by the frame for individually adjusting said blocks relatively to the comb rail and the carriage rail, and means for securing said blocks in their adjusted position.
- 15 7. In a links and links knitting machine, in combination, a frame, a comb rail supported upon said frame, a carriage rail, and means for supporting said carriage rail from said comb rail at a plurality of points between its ends, including a plurality of blocks carried by said comb rail, a plurality of bracket arms secured to the frame and projecting to a point beneath the carriage rail, means comprising a threaded bolt carried by the free end of each of said bracket arms for engagement with its respective block for adjusting the block relative to the carriage rail and the comb rail, and means having engagement with the comb rail for securing said blocks in their adjusted position.
- 20 8. In a links and links knitting machine, in combination, a frame, a carriage rail, a plurality of separate supporting means for supporting said carriage rail at separate points intermediate of its ends, said separate supporting means being independently adjustable in a vertical and lateral direction.
- 25 9. In a links and links knitting machine, in combination, a frame, a carriage rail, a plurality of separate supporting means for supporting said carriage rail at separate points intermediate of its ends, said separate supporting means being independently adjustable in a vertical and lateral direction.
- 30 10. In a links and links knitting machine, in combination, a frame, a carriage rail, and means for adjusting said carriage rail in a lateral direction.
- 35 11. In a links and links knitting machine, in combination, a frame, a carriage rail, and a plurality of separate supporting means for supporting said carriage rail at separate points intermediate of its ends, said separate supporting means being independently adjustable in a lateral direction.

LADISLAUS ROBACZYNSKI.
